REFLECTIVE BICYCLE HANDLEBAR

Carlton P. Pawsat and Robert F. Humlong, Maysville,
Ky., assignors to Wald Manufacturing Company, Inc.,
Maysville, Ky.

Filed Oct. 26, 1970, Ser. No. 25,649

Term of patent 14 years

Int. Cl. D12—16

U.S. Cl. D90—11

FIG. 1 is a perspective view of the front and right side of a reflective bicycle handlebar showing our new design. FIG. 2 is a front elevation view of FIG. 1.

FIG. 3 is an elevation view of the right side of FIG. 2. We claim:

The ornamental design for a reflective bicycle handlebar, as shown.
